DESIGN FOR A WRIST LOCKET OR SIMILAR ARTICLE

James H. Petter, New York, N. Y.

Application October 6, 1942, Serial No. 108,440

Term of patent 14 years

To all whom it may concern:

Be it known that I, James H. Petter, a subject of the King of England, having applied for citizenship in the United States of America and awaiting final papers thereon, and a resident of the city, county, and State of New York, have invented a new, original, and ornamental Design for a Wrist Locket or Similar Article, of which the following is a specification, reference being had to the accompanying drawing, forming part thereof, in which:

Fig. 2 is a side elevational view thereof;

Fig. 3 is an end elevational view thereof; and

Fig. 4 is a section on the line 4—4 of Fig. 1.

I claim:

The ornamental design for a wrist locket or similar article, as shown.

JAMES H. PETTER.
